(57) **CLAIM**

I claim the ornamental design for a visor magnifier with LED, as shown and described.

DESCRIPTION

FIG. 1 is an isometric view of a visor magnifier with LED showing my new design;

FIG. 2 is a front view thereof;

FIG. 3 is a rear view thereof;

FIG. 4 is a right side view thereof;

FIG. 5 is a top plan view thereof; and,

FIG. 6 is a bottom plan view thereof.

The broken lines showing is for environmental purposes only and form no part of the claimed design.
